UNITED STATES PATENT OFFICE.

HUGO ULLMANN, OF ST. GALLEN, SWITZERLAND.

TELEPHONOGRAPH.

1,310,900.

Specification of Letters Patent. Patented July 22, 1919.

Application filed March 26, 1919. Serial No. 285,352.

To all whom it may concern:

Be it known that I, HUGO ULLMANN, a citizen of the Swiss Confederation, and residing at St. Gallen, Switzerland, have invented certain new and useful Improvements in Telephonographs, of which the following is a specification.

The present invention has reference to certain new and useful improvements in telephonographs, or telescribes and relates more particularly to an apparatus and installation which allows of recording the telephonic conversation of two connected parties during all of the conversation or only part of it, either party being able to throw his telephonographic unit into or out of operative connection at will without in any way interfering with the operation of the ordinary telephonic unit, so that conversations of special importance may be permanently recorded by either party without the other party being aware of it.

In order to make my invention more readily understood I will now describe it with reference to the accompanying drawings in which Figure 1 is a side view of the apparatus, with the facing casing wall removed; Fig. 2 is a top view with the cover partly broken away; Fig. 3 is a vertical section on line A—A of Fig. 1; Figs. 4 and 5 respectively represent side and edge views of a detail of the driving works, and Fig. 6 is a diagram of the wiring connections.

The casing 1 is provided with a two-part cover 2 and a similarly divided side wall 3, and the front wall 4 with the cover flap 2^a and the side wall flap 3^a can be folded up on hinges 5 to give access to the apparatus mounted in the casing 1. In the inclosure B is provided a clockwork of suitable construction, which is wound up by means of the outwardly protruding key b and drives the shaft 6. The works are provided with the usual train of wheels and with a governor not specially shown, a protruding pointer 7 controlling the operation of the governor. Obviously, in place of a spring driven clockwork also any other driving mechanism, for instance an electric motor may be used. In the train of wheels is arranged an arresting wheel 8 riding loosely on the hub 36 fixed on the shaft 35 and presenting a laterally extending tooth 37 designed for coöperation with a cut-out 38 of the hub 36 with contact faces or walls 39 and 40 (Figs. 4 and 5). Within the cut-out 38 there is interposed

between the tooth 37 and the wall 39 a compressible spring 41. The stop wheel 8 is controlled by a pawl 9, fulcrumed at 10, and forming the armature of an electromagnet 12 fixed to the casing wall by a bracket member 11. The driving shaft 6 is drivingly connected by the belt drive 13 to the shaft 14 which latter is one-sidedly supported in the bearing 15 and which exchangeably supports the recording wax cylinder 16 on the usual conical mandrel. A toothed wheel is also fixed on this shaft 14 and gears with a wheel 18 (Fig. 3), and the latter in turn meshes with the toothed wheel 19 fixed on the screw spindle 20 housed in the guide tube 21. This latter is secured at one end in the arm 15^a of the bearing 15 and at the other end in the upright 22 and serves to guide the carriage 23. This latter supports the telescribing receiver 24, which essentially is in the form of an ordinary watch case receiver with a recording stylus fixed to the diaphragm, which stylus 25 coöperates with the wax cylinder 16. The screw spindle 20 serves for the feed of the carriage 23 along the guide tube 21 by means of a feed screw segment which at its one end meshingly coöperates with the screw spindle 20 and at its other end supports the recorder carriage, and a setting handle 26 is rigidly secured to this screw segment, which latter extends through a longitudinal slit in the guide tube and can be brought into or out of operative contact with the screw spindle by respective manipulation of the handle 26. All these parts and their coöperation are well known in the art, and for that reason need not be particularly described here, all the more as they form no part of the invention proper.

From the carriage extends downwardly the lever arm 27 whose lower end is in the shape of a half-circle adapted to coact with a guide and contact rod 28 arranged below the recording mandrel parallel to the tube 21. This rod 28, which is composed of two halves 28^a and 28^b electrically insulated as at Z (Fig. 6), is electrically insulated from its end supports 22 and 15^a respectively. To the handle 26 is secured by the intermediary of the link 29 the lever arm 30 whose lower end loosely encircles the rod 28 so that it can readily be traveled thereon in longitudinal direction by the arm 27 and can also rock about it. Near the lower journaled end of the lever arm 30 is provided a laterally extending tooth or cam 30^a adapted

to coöperate with the lower end of the depending arm 27 in such manner that, depending upon the manipulation of the handle 26, the lower curved end of the arm may 5 be let down to contact with the divided rod 28 or may be lifted off out of contact therewith. The curved extremity of the arm 27 supports two insulated contact segments 27^a and 27^b designed to respectively contact with 10 the facing half-cylinder conductors 28^a and 28^b for closing an electrical circuit through the magnet system in the recorder 24. The upper contact member 27^b contacts with a contact bar K when out of contact with the 15 half-cylinder 28^a. A pointer 31 is associated with the handle 26 and the latter travels in a transverse slot 32 in the casing cover, a scale 26^a being provided along this slot over which the pointer 31 travels indicating 20 thereby the momentary position of the recording stylus relative to the wax cylinder.

The wiring is that of a normal telephone hook-up with local microphone battery, and the transmitter M as well as the receiver H 25 are of the usual type. The electrical circuit for the transmitter is indicated by 33 and that for the receiver by 34. From circuit 33 a branch 33^a leads to the electromagnet 12, from there over the feed screw spindle 20 to the magnet system in the recorder 24 and thence to the half-cylinder 28^a. From the receiver circuit 34 a branch 34^a leads to the recorder 24 and thence to the lower contact segment 27^a. The upper segment 35 27^b is connected by the wire 33^b to the transmitter, and the lower half-cylinder 28^b is connected by the branch 34^b to the receiver circuit. A third branch wire 33^c connects contact member K with the transmitter circuit 33. The branch 33^a includes the electromagnet 12, which as above described by 40 means of the pawl 9 controls the mechanism for operating the recorder mandrel, and a non-inductive resistance or condenser 45 C is connected in parallel, to deflect the voice currents from the electromagnet which is subject to self-inductance.

The described apparatus can be operated by local battery as well as by central battery 50 current and is preferably arranged close to the telephone station. The branch circuits 33^a, 33^b and 33^c are cut into the transmitter circuit 33, and the two branches 34^a and 34^b are connected to the two terminals for 55 the second receiver usually provided in a telephone station.

In the inoperative position of the apparatus the handle 26 assumes the position indicated in Fig. 3 by the dash-dot line, the 60 bipolar contact end of the arm 27 is out of contact with two-part contact rod 28 and the circuits 33, 33^a, 33^b and 34, 34^a, 34^b are interrupted, and the phonograph unit is thus disconnected. The subscriber is 65 called up over the ordinary call circuit,

which forming no part of the invention is not specially shown in the drawing. By taking the receiver H off its switch hook G contact is made between f and f', which closes the transmitter circuit 33 which includes the 70 induction coil u, the wire 33^c, contact K, wire 33^b, transmitter M, hook G and local battery S. If the person at the telephone now wishes to phonographically record the 75 conversation coming and going over the line the handle 26 is laid over into the full line position in Fig. 3, which movement causes the lever arm 30 to swing in the direction of the arrow a, when its tooth 30^a will allow the arm 27 to contact with the 80 two-part contact rod 28, the recorder 24 being let down simultaneously onto the wax cylinder 16. At the same time the spindle 20 and the traveling carriage 23 are inter-coupled. The contact member 27^b contacts 85 with the contact member 28^a and the contact member 27^a with the contact member 28^b, which completes the several circuits. By the closure of the circuit 33 the control magnet 12 is excited, the armature 9 is attracted and the clockwork for driving the phonograph can start. In starting, the stop wheel 8 by reason of the expanding spring 39 will at first gain on the hub 36 until the tooth 37 contacts with the wall 40 of 90 the cut-out 38. The rotary motion of the 95 clockwork is transmitted from the shaft 6 to the shaft 14 and thence by the gear train 17, 18 and 19 to the spindle 20, with the result that the wax cylinder on the shaft 100 14 is rotated and simultaneously the carriage 23 with its recorder 24 is traveled parallelly along the shaft 14.

The current pulsations produced in the transmitter M excite the electromagnetic 105 system in the recorder 24, which latter now lies in the circuit 33 and cause its stylus to record the conversation on the wax cylinder, and they also are transmitted by the induction coil u over the line wires L¹, L² to 110 the other party. Similarly the voice currents coming in over these wires from the other end of the line pass through the receiver H and also through the electromagnet system in the recorder 24 and are thus like- 115 wise recorded on the wax cylinder.

If, at the end of the conversation, the receiver H is placed back into its switch hook, the pawl armature 9 is immediately dropped by the magnet 12 and engages in 120 the stop wheel 8, which however does not stop the driving works at once but allows it to continue its operation for a short period of time until the spring 41 is fully compressed between the wall 39 and the tooth 125 37. By this retarded stopping action the wax cylinder can still make a few revolutions, for the purpose of spacing apart successively recorded conversations, so that they do not run together and can readily be 130

told apart when reproducing them again at a future time.

The handle 26 is now brought back again to the normal "off" position, which inter-
5 rupts the circuit through the phonographic recorder and also lifts the latter off the wax cylinder, so that it can readily be removed from its mandrel. With the handle in the normal, inoperative position, all phonographic connections are broken and the apparatus is connected up for ordinary telephonic conversation. Obviously, in place of the cylindrical recording member, also a disk recording member may be used.

10 15 What I claim is:—

1. In a telephonographic system for at will recording all or part of the conversation between two telephonically connected parties, the arrangement that a manually operable contacting member, comprising a handle and a depending contact arm, in its operative position causes a recorder with its recording stylus to descend into operative contact with a wax cylinder and connects 20 the recorder across the receiver circuit as well as across the transmitter circuit of the telephone station, and also by the local battery current causes the electromagnetic release of a driving mechanism for operating 25 the phonographic unit, which contacting member in its inoperative position closes the transmitter circuit direct and cuts out the phonograph unit, substantially as set forth.

2. In a telephonographic system comprising a telephone unit and a phonograph unit 35 and means for at will electrically intercoupling the two units, in combination, a transmitter circuit including a transmitter, a local battery, an induction coil primary winding, an electromagnet and an armature operated thereby, and a condenser in parallel with said electromagnet; a receiver circuit including the induction coil secondary winding and the receiver; the phonographic unit comprising a driving mechanism controlled as to starting and stopping by said electromagnetically operated armature in 40 45 said transmitter circuit and operating in the well known manner the mandrel supporting the wax cylinder and the traveling carriage supporting an electromagnetic recorder, and hand lever means for respectively moving said recorder into operative contact with the wax cylinder and for simultaneously closing the several circuits in 50 55 such manner that the incoming and outgoing voice currents are forced to pass through the electromagnetic systems of said recorder, and for lifting said recorder out of contact with the wax cylinder and simultaneously electrically disconnecting the phonographic unit and closing the ordinary telephone system direct, substantially as shown and described.

HUGO ULLMANN.
